(57) **CLAIM**

The ornamental design for a headphone, as shown and described.

DESCRIPTION

FIG. 1 is a perspective view of a headphone showing the new design;

FIG. 2 is a front elevational view thereof;

FIG. 3 is a rear elevational view thereof;

FIG. 4 is an exterior side elevational view thereof;

FIG. 5 is a bottom view thereof;

FIG. 6 is a top view thereof; and,

FIG. 7 is an interior side elevational view thereof, viewed from line 7-7 in FIG. 6.

The claim encompasses the mirror image embodiment thereof.

The broken lines shown in the drawings depict portions of the headphone that form no part of the claimed design.

1 Claim, 6 Drawing Sheets
